(57) **CLAIM**

The ornamental design for a shower base, as shown and described.

DESCRIPTION

In a preferred embodiment, the nature of this product is as a shower receptor for a shower plumbing fixture.

FIG. 1 is a top, right, front perspective view of a shower receptor of my new design;

FIG. 2 is a top plan view thereof;

FIG. 3 is a side elevational view thereof shown turned clockwise 45 degrees from the FIG. 2 position;

FIG. 4 is a front elevational view thereof, the right side elevational view thereof being a mirror image of the front view shown;

FIG. 5 is a left side elevational view thereof, the rear elevational view thereof being a mirror image of the left side shown;

FIG. 6 is a bottom plan view thereof;

FIG. 7 is a top, right front perspective view of another embodiment of my new design;

FIG. 8 is a top plan view thereof;

FIG. 9 is a side elevational view thereof shown turned clockwise 45 degrees from the FIG. 8 position;

FIG. 10 is a front elevational view thereof, the right side elevational view thereof being a mirror image of the front view shown;

FIG. 11 is a left side elevational view thereof, the rear elevational view thereof being a mirror image of the left side shown; and,

FIG. 12 is a bottom plan view thereof.

The broken line representations of a drain in FIGS. 1–2, 5–8 and 11–12, and environmental wall structure in FIGS. 1–6 are for the purpose of illustration only, and form no part of the claimed design.
